UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

SEAM-SPACER FOR SEWING-MACHINES.

1,109,445.

Specification of Letters Patent. Patented Sept. 1, 1914.

Application filed May 11, 1907. Serial No. 373,070.

To all whom it may concern:

Be it known that I, CHESTER McNEIL, a citizen of the United States, residing at Chicago, in the county of Cook, State of Illinois, have invented certain new and useful Improvements in Seam-Spacers for Sewing-Machines, of which the following is a description, reference being had to the accompanying drawing, and to the letters 10 and figures of reference marked thereon.

The invention relates to new and useful improvements in sewing machines having stitching elements so disposed as to form spaced lines of stitching, and more especially to a sewing machine of this character which includes devices for forming tucks.

An object of the invention is to provide means whereby lines of stitching may be formed which in the finished article are a greater distance apart than the distance between the stitching elements.

A further object of the invention is to provide devices coöperating with the stitching elements in a machine of the above character, whereby spaced tucks may be simultaneously formed which tucks will be greater distance apart in the finished article than the distance between the stitching elements.

A further object of the invention is to provide devices of the above character which include means for adjusting the distance between the sitched tucks.

These and other objects will in part be obvious and will in part be hereinafter more fully disclosed.

In the drawings which show an embodiment of my invention, Figure 1 is a sectional view through the presser foot and throat plate embodying my invention. Fig. 2 is a top plan view of a presser foot and the work support with the invention applied thereto. Fig. 3 is a front plan view. Fig. 4 is a sectional detail showing the relative position of the fabric in my improved seam spacer when the machine is operating to form spaced tucks. Fig. 5 is a detail partly in section showing the relation of 50 the needles and loopers to the tuck forming members.

The invention, as illustrated in the draw-

ings, is applied to a presser foot for making tucks in the fabric. Said presser foot 1 is provided with grooves 2, 3, in the face 55 thereof which coöperate with ribs or fins 4, 5, respectively, mounted on the throat plate of the machine. These grooves and ribs are arranged parallel and extend beyond the needle openings 6, 7, to the cut 60 away portions 8, 9, in rear of the needle opening. As the fabric passes beneath the presser foot and over the ribs or fins, it will be formed into tucks which are secured by suitable stitch forming mechanism preferably comprising sets of needles, each set having a looper which operates to secure the stitches together on the under side of the fabric and thus secure the tuck. After the tuck is formed, the inclined rear portions 70 of the presser foot formed by the cut away portions 8 and 9, operate to turn down the tucks flat upon the fabric. This presser foot is the same as that shown in the patent to R. G. Woodward and C. McNeil, 821774, 75 granted May 29, 1906, and forms no part of the present invention.

By the above construction, it will be noted that parallel tucks may be formed in a fabric, but that the distance between said 80 tucks is necessarily the distance between the ribs on the throat plate. In order to adjust the distance between the tucks without substituting another presser foot and adjusting the distance between the needles, I have 85 provided an adjustable rib 10, which, as shown in the drawing, is carried by the presser foot. Said presser foot is provided with a groove 11 centrally thereof in which the rib 10 is placed. Said rib 10 has fixed 90 thereto posts 12 and 13, which extend upward through suitable openings in the presser foot. A plate 14, having openings in its ends, is placed upon the posts 12 and 13 and secured thereto. Springs 15 and 16 95 are placed upon the posts 12 and 13 between the plate 14 and the presser foot. The upper surface of the presser foot surrounding the posts 12 and 13 is bored out to receive the springs 15 and 16. An adjusting screw 17 passes through the plate 14 and is threaded into the presser foot.

It will be noted from the above construction that when the screw 17 is turned in,

the plate 14 is moved toward the upper surface of the presser foot and the rib or fin 10 is moved downward out of the groove 11 in the presser foot. And when the screw 17 is turned outward, the springs 15 and 16 will move the rib or fin into the groove in the presser foot.

The throat plate or work support 18 is provided with a groove 19 which receives 10 the rib or fin 10. When the material to be operated upon is placed beneath the presser foot, the ribs 4 and 5 will form tucks in the material which tucks will be stitched as they pass to the needles of the machine. The material between the tucks is bent downward by the rib or fin 10 into the groove in the throat plate and it will be obvious that when said fin or rib 10 is adjusted so as to extend a greater or lesser distance into the groove 20 in the throat plate, more or less of the material will be taken up by said rib and by the adjustment of this rib or fin, therefore, the distance between tucks may be varied.

It is obvious that the rib or fin may be 25 placed on the throat plate and the groove formed in the presser foot. I, however, prefer to mount the rib on the presser foot for the reason that the adjusting screw is in a more convenient position for access in adjusting 30 the position of the rib.

It is obvious that my adjustable rib for varying the distance between tucks may also be used for varying the distance between 35 lines of stitching, where, for example, it is desired to space the rows of stitches a greater distance than the distance between the needles of the machine.

It is obvious that the minor changes in the details of construction may be made 40 without departing from the spirit of my invention.

Having thus particularly described my invention what I claim as new and desire to secure by Letters Patent is:—

45 1. The combination with a plurality of needles and complementary stitch forming mechanism of means coöperating therewith to form and stitch simultaneously a plurality of tucks and means for varying the distance between the lines of stitching forming the tucks.

50 2. The combination with a plurality of needles and complementary stitch forming mechanism and means coöperating therewith for forming independent stitched tucks and adjustable means located between said tuck forming devices for varying the distance between said tucks.

55 3. The combination with a plurality of pairs of needles, a presser foot, a work support means coöperating with the needles to form spaced tucks, a rib or fin, carried by one of said parts and located between said pairs of needles, the other of said parts having a groove for receiving said rib or fin

and means for adjusting the position of said rib or fin whereby the distance between the tucks may be varied.

4. The combination with a plurality of needles and complementary stitch forming 70 mechanism of a presser foot, a rib carried by said presser foot, means for adjusting said rib, and a work support having a groove to receive said rib.

5. A presser foot having spaced grooves 75 formed in the lower face thereof, for receiving tucks, a rib connected to the presser foot and located between said grooves and means for adjusting the amount of projection of the rib beneath the presser foot. 80

6. A presser foot having spaced grooves on its under face for receiving tucks, and a groove intermediate said spaced grooves for receiving a projecting rib, a rib located in said groove and projecting below the under 85 face of the presser foot, and means for adjusting the amount of projection of said rib.

7. In a sewing machine, including a presser foot and a coöperating throat plate, said throat plate being provided with a groove, 90 a fin carried by said presser foot and registering with said groove in said throat plate, and means to adjust the overlapping of said fin in said groove.

8. In a sewing machine, the combination 95 of a plurality of needles, a presser foot and a coöperating throat plate, said throat plate having a groove therein, located between the needles, said presser foot having a fin mounted thereon and registering with said groove 100 in the throat plate, and means for adjusting the overlapping of the fin in said groove.

9. A presser foot having a groove in its under face, a rib located in said groove, 105 guiding posts attached to said rib and extending through said presser foot and an adjusting screw for adjusting said rib.

10. A presser foot having a groove in its under face, a rib located in said groove, guiding posts attached to said rib and extending through said presser foot, springs 110 surrounding said guiding posts and normally holding said rib within said groove and an adjusting screw for moving said rib out of said groove. 115

11. A presser foot having a groove in its under face, a rib mounted in said groove, guiding posts attached to said rib and extending through said presser foot, a plate connecting the upper end of said posts, 120 springs intermediate said plate and the upper face of said presser foot and an adjusting screw passing through said plate into said presser foot.

12. The combination of a presser foot and 125 a work support, one of said parts having a groove, a rib mounted in said groove, means for adjusting said rib, and the other of said parts having a groove to receive said rib.

13. The combination with a plurality of 130

needles and mechanism coöperating therewith to simultaneously form a plurality of tucks, of means for spacing said tucks a greater distance than the distance between 5 said needles.

14. The combination with a plurality of needles and mechanism coöperating therewith to simultaneously form a plurality of tucks of an adjustable means for spacing

said tucks a greater distance than the distance between said needles and for varying said distance.

In testimony whereof I affix my signature, in presence of two witnesses.

CHESTER McNEIL.
